FLAT BED AND CYLINDER PRINTING PRESS

William G. Montgomery and Samuel A. Huffman, Marietta, Ohio; said Huffman assignor to said Montgomery

Application November 24, 1950, Serial No. 197,218

18 Claims. (Cl. 101—191)

Our invention relates to a flat bed and cylinder printing press. It relates, more specifically, to a printing press of the reciprocable bed and two revolution cylinder type. Our invention is especially applicable to multi-color presses, where a number of colors are to be printed, but most of its features are also applicable to single-color presses.

The demand by printers for greater production and higher efficiency has led to the design of presses which will operate at higher and higher speeds. There are definite limitations, however, to the maximum possible speeds obtainable with known designs.

It is well-known in the art that in a flat-bed and cylinder printing press, the sheet to be printed is carried around a revolving cylinder in such a manner that it is brought into contact under great pressure with a flat inked form which form is carried by a reciprocating type bed. There are in general use two types of flat-bed and cylinder printing presses. The first and most common is known as the two-revolution press. The second is known as the stop-cylinder press.

The existing two-revolution presses contain either one or two printing cylinders which revolve two revolutions, per cycle, at a constant or uniform speed, one revolution during the printing stroke of the type bed and the other revolution during the return stroke of the type bed. Each printing cylinder engages the reciprocating type bed only during a portion of the printing stroke. The type bed travels at the same constant or uniform linear speed as the printing surface of the cylinder or cylinders during the major portion of each of its strokes. The type bed is reversed at each end of its constant speed of travel by a crank, which crank revolves a constant number of revolutions per minute. The mechanism for reciprocating the type bed in this manner is known as a bed motion.

There are two bed motions now in general use on two-revolution flat-bed and cylinder presses. These are known either as a two-to-one bed motion or as a three-to-one bed motion. If the crank which reverses the type bed at the end of its constant speed stroke, revolves two revolutions per each cycle or two strokes of the type bed (one stroke forward and one stroke reverse), then the bed motion is known as a two-to-one bed motion. If the crank which reverses the type bed at the end of its constant speed stroke revolves three revolutions per each cycle of the type bed, then the bed motion is known as a three-to-one bed motion.

In the stop cylinder flat-bed and cylinder printing press, the printing cylinder revolves in synchronization with the type bed on the complete printing stroke of the type bed and stops completely on the opposite or reversing stroke of the type bed. The type bed travels by modified harmonic motion during the entire printing and return stroke. The modified harmonic motion is usually a crank and connecting rod.

It has been proposed in the prior art to provide a flat-bed and cylinder printing press wherein the bed is

driven with a full or modified harmonic motion and the cylinder is rotated continuously through two revolutions during each cycle of the bed motion. In this press it has been proposed to drive the cylinder with a variable 5 crank drive by means of which it was attempted to bring the cylinder into synchronization with the bed movement only during a portion of the printing stroke, the cylinder being out of synchronization with the bed throughout the remainder of the bed motion.

10 There are two principal reasons why operating speeds cannot be increased substantially with existing designs of two-revolution flat-bed and cylinder presses, employing either the two-to-one or the three-to-one bed motion. First, the surface speed of the printing cylinder becomes 15 so great at the higher speeds that sheets are either damaged when taken from the feed board by the cylinder grippers or cannot be taken at all. The sheets are accelerated from zero to the full surface speed of the printing cylinder instantly. It can, therefore, be readily seen that this action is so extremely severe that taking sheets 20 at higher speeds is thus impossible without the provision of additional costly mechanism acting to accelerate the sheet more gradually. Second, operating speeds cannot be substantially increased because of the magnitude of the forces of acceleration and deceleration of the reciprocating type bed assemblies. These forces increase so rapidly, as speed increases, that the presses move back and forth on the floor. If the press is bolted down to the floor to prevent movement thereon, damage to its mechanism 25 is inevitable. Counterbalancing the forces of existing bed motion designs is extremely difficult if not impossible.

With regard to the stop-cylinder press, one of the chief disadvantages of this type of press is the difficulty of removing the printed sheet from the cylinder. The transfer means for removing the sheet must pull the printed 30 sheet off the cylinder since it cannot be rolled off such cylinder when the cylinder is stopped. This difficulty is greatly increased with the larger size sheets. In connection with the feeding of the sheet in this type of press, if the sheet is fed to the top of the cylinder, a larger 35 diameter printing cylinder is required which makes it necessary to provide a longer stroke for the bed and this, in turn, results in slower speed for a given size sheet. On the other hand, if the sheet is fed to the underside of the printing cylinder, it will be apparent that the feeder will 40 have less capacity due to the lowering of the feed point at a distance substantially corresponding to the diameter of the cylinder causing more frequent shut downs for reloading with consequent loss of production. Furthermore, when the sheet is fed at the lower side of the cylinder, the printed side of the sheet would be down during 45 the transfer to the next printing cylinder, if the press is a multi-color press, and during transfer to the delivery unit. Consequently, almost certain smearing and smudging 50 of the sheets would occur.

Existing two-color flat-bed and cylinder printing presses have a transfer cylinder which has a diameter equal to one-half the diameter of the printing cylinders and which is located between the two printing cylinders for the purpose of carrying a sheet from one cylinder to the other. 55 This arrangement has a number of disadvantages. In the first place, during the transfer of the sheet from one cylinder to the other, the wet ink of the printed surface is towards or next to the transfer cylinder surface. Consequently, great care and precaution must be taken and means provided to prevent the printed sheet from being smeared or smudged. Also, thick sheets, such as cardboard, are difficult or even impossible to bend around the transfer cylinder without cracking or other such damage to the sheets. Furthermore, the transfer cylinder is in a 60 fixed position between the printing cylinders and cannot be moved away from either of the cylinders at any time 65

and, therefore, it is very difficult to make-ready each of the printing cylinders because of interference by the transfer cylinder. In addition, the inkers are necessarily located on opposite sides of each of the printing cylinders and are, therefore, not identical, being right and left hand. Many of the parts of the two inkers are different because they are right and left hand. Adjustments and settings, therefore, are different and contrary to standard single color practice requiring the most experienced pressmen to make these adjustments and settings and it is also more difficult to adjust the two type forms which must necessarily be located differently than in single-color presses. The arrangement of the transfer cylinder relative to the printing cylinders makes it impossible to design a press with such a transfer arrangement to print more than two colors. Furthermore, with this transfer arrangement, cylinders of larger diameter are required and, consequently, a longer stroke of the bed is required than for single-color presses for printing the same size sheet. All of these disadvantages of prior art two-color presses are true of the two-revolution cylinder presses and the stop-cylinder presses discussed above.

A press in which it was attempted to synchronize the cylinder with the bed movement only during a portion of the printing stroke was proposed many years ago. However, this type of press has not gone into use, apparently because of the difficulty or impossibility of accurately bringing the cylinder into synchronization for the particular period during the printing stroke. With such an arrangement, where the cylinder is not synchronized at all times, running clearances, which are necessary between the moving driving parts, apparently result in inaccuracies in the synchronization. With this type of press, a large size cylinder and a longer bed stroke is required in order to print a given size sheet than would be required if the cylinder were synchronized on the complete printing stroke as, for example, in a stop-cylinder press. Therefore, this press will operate at a somewhat slower speed depending upon this ratio. It can also be shown that the cylinder grippers will take the sheet from the feedboard at a somewhat higher speed than would be the case if the cylinder were fully synchronized.

One of the objects of our invention is to provide a two-revolution flat-bed and cylinder printing press with full harmonic bed motion and with the surface of the printing cylinder or cylinders perfectly synchronized with the movement of the type bed at all times.

Another object of our invention is to provide a press having means for reciprocating the type bed which means is so designed and constructed as to substantially counter-balance the forces created by the reciprocation of the type bed so that the press will not move on the floor even when operated at speeds substantially greater than the maximum speeds of existing flat-bed presses without bolting the press to the floor or embedding it in concrete.

Still another object of our invention is to provide a press of the type indicated which can be operated at speeds far in excess of those of conventional flat-bed presses without injury to the sheets of paper being fed into the press because the cylinder or cylinders on our press take the sheets at or near the end of the stroke of the bed when the cylinder or cylinders are stopped or almost stopped.

An additional object of our invention is to provide a press of the type indicated above wherein the mechanism for moving the bed and cylinder or cylinders is so designed and so located as not to interfere with reinforcement of the main frame directly under the locations wherein the printing impressions are taken, a feature which is so necessary for the required rigid impressions.

A further object of our invention is to provide a press of the type indicated with means for raising and lowering the printing cylinder or cylinders away from and towards the type bed, which means is operated directly underneath the type bed and is, therefore, much more simple

and compact and has far more more rigidity than prior art arrangements which latter extend practically to the floor.

Another object of our invention is to provide a press of the type indicated with means for driving the printing cylinder or cylinders which is completely under the control of the bed-driving means on both strokes of the bed and wherein it is not necessary to lift the cylinder driving gears partly out of mesh as in existing two-revolution flat-bed presses and which results in excessive play or back-lash and noisy operation, the gears on our press remaining in full mesh even when the cylinder or cylinders are raised to permit passing of the form or forms on the return stroke of the bed.

Still another object of our invention is to provide a two-revolution cylinder printing press with full harmonic bed motion and having a plurality of impression cylinders cooperating with a plurality of forms on a single reciprocable type bed, so that the press is suitable for multi-color work, the cylinders being spaced apart sufficiently so as not to interfere with the make-ready operation, the technique of operation thus conforming to that of single color presses with which practically all operators are familiar.

Another object of our invention is to provide a multi-color printing press of the type indicated above which is provided with transfer means including registering devices which will carry sheets from one cylinder to the next in absolute register.

A further object is to provide a multi-color press of the type indicated wherein the transfer means is such that the sheets are carried from cylinder to cylinder with nothing touching the printed side thereof so as to eliminate any danger of smearing.

Another object of our invention is to provide a multi-color press of the type indicated wherein the printed sheets will be transferred from one cylinder to the next in flat condition which makes it possible to handle heavy cardboard or the like without cracking or other damage thereto.

Various other objects will be apparent from the following description and the drawings.

The preferred embodiment of our invention is illustrated in the accompanying drawings wherein similar characters of reference designate corresponding parts and wherein:

Figure 1 is a plan view, partly broken away, of a press constructed according to our invention.

Figure 24 is an enlarged plan view of the opposite end of the gripper bar.

Figure 25 is an end view of the structure shown in Figure 24.

Figure 26 is a sectional diagrammatic view illustrating the gripper bar and associated cylinder, the grippers on the gripper bar being in engagement with the sheet and the grippers on the cylinder being in position to engage the sheet.

Figure 27 is a similar view but showing both sets of grippers in engagement with the sheet.

Figure 28 is a similar view but showing the cylinder grippers in engagement with the sheet and the grippers on the gripper bar released from the sheet.

Figure 29 is a diagram illustrating the relative movements of the main crank; the clutch actuating cam; and the housing of the cylinder driving unit of the press.

Figure 30 is a diagrammatic view illustrating a press, constructed according to our invention, for printing four colors.

With reference to the drawings, we have illustrated the general structure of our press in Figures 1 to 3. The press shown includes the single bed 30 which is mounted on the main frame 31 for reciprocation longitudinally thereof in a horizontal plane and two transversely disposed impression cylinders 32 and 33 which are carried by the frame and are located above the path of movement of the bed, the cylinders having their transverse axes spaced longitudinally of the press. These two cylinders are adapted to cooperate with two printing forms F which will be suitably removably attached to the bed at proper locations spaced longitudinally of the bed. It will be apparent from the following description that the bed is reciprocated with a full harmonic motion, the cylinders are rotated in the same direction at all times regardless of the direction of movement of the bed, the rotation of the cylinders is timed with the movement of the bed so that cylinder rotation and bed motion are in exact synchronism at all times, and the cylinders are in contact with the forms during the movement of the bed in one direction, that is during the printing stroke, but are lifted

therefrom during movement of the bed in the opposite direction, that is, during the return stroke.

In the press illustrated, we have shown the bed horizontally disposed. However, our invention is not necessarily limited to a horizontal press but the features thereof can apply to a vertical press. The press shown in Figure 1 to 3 is for printing two colors, since it is shown with two impression cylinders, but it is to be understood that any number of cylinders may be used with the same number of forms supported on the bed in properly spaced relationship, the number depending upon the number of colors desired. For example, in Figure 30, we have shown a press with four cylinders and four beds. Transfer of the sheets from one cylinder to another is accomplished by means of a novel transfer mechanism or unit indicated generally by numeral 34. The transfer unit 34 will move vertically with vertical movement of cylinders 32 and 33 and will be driven in synchronism with rotation of the cylinders. It will be apparent that, if desired, we may provide our press with only one cylinder and in that case, the transfer unit 34 will not be used.

The frame 31 is illustrated best in Figures 1, 2 and 3. It may assume various forms but is preferably formed in one piece and includes the side frame members 35 and 36, the open end frame members 37 and 38 and the bed supporting track members 39 and 40 which extend the full length of the frame and which connect with the end members 37 and 38. It will be noted from Figure 3 that the side frame members 35 and 36 extend a substantial distance above the bed supporting track members 39 and 40. In addition, as shown in Figures 1, 6 and 11, the frame includes the heavy transverse beam sections 41 and 42 disposed directly below the respective cylinders 32 and 33 and with their upper surfaces just slightly below the upper edges of the tracks 39 and 40. These beam sections 41 and 42 are integrally joined to the side members 35 and 36 and the tracks 39 and 40. As will later appear, since these heavy beam sections are located close to the upper side of the frame and directly below the cylinders 32 and 33, they will serve to take the thrust forces created when the cylinders and the forms on the bed 30 are brought into unyielding engagement. We have designed the bed motion and cylinder driving mechanism, to be described hereinafter, in such a manner that it is possible with this press to locate the beam sections 41 and 42 directly beneath the bed and the cooperating cylinders where they will more effectively absorb the forces created during the unyielding impression of the cylinders on the bed which occurs during the printing operation.

As indicated above, the motion imparted to the bed will be a full harmonic motion. The mechanism for producing this motion is illustrated in Figures 1 to 5, inclusive. This mechanism is a crank mechanism which includes a Scotch yoke arrangement. As shown in Figure 1, a flywheel 43 is provided outside of but recessed within the side support 35 of the frame 31. This flywheel is keyed on an inwardly extending transverse shaft 44 which is supported on bearing 45 in track 39 and bearing 46 in side member 35. This shaft is driven continuously, when the press is operating, by means of a sprocket 47 keyed thereon within the side support 35, as shown in Figures 1 and 2. This sprocket is driven by a chain 48 which is driven by an electric motor 48a supported at one end of the press within the frame 31 or by any other suitable power unit. The shaft 44 has a pinion 49 (Figure 2) keyed on its inner end which engages with the large crank gear 50. This gear 50 is keyed on the inner end of a shaft 51 which is suitably mounted for rotation in a bearing 52 (Figures 1 and 3) in side member 35 and in a bearing 53 in track member 39. Shaft 51 also carries a cam 54 (Figure 3) which is keyed thereon and which is provided for a purpose to be explained later. Eccentrically carried by the gear 50 is a crank pin 55, shown

best in Figures 2 and 3, which carries a roller 56 that is mounted thereon by means of a roller bearing 57.

The roller 56 operates in a vertical slot or groove 58 formed in an enlarged vertically disposed portion 59 of a Scotch yoke 60. This yoke 60 is illustrated best in Figures 1 to 3, and 5. It includes the vertical portion 59 (Figure 5) and the horizontal extending integral portion 61. At the end of the portion 61 and at the upper edge thereof a rack bar 62 is rigidly attached in a suitable manner, preferably removably. It will be noted best from Figure 1 that the portion 59 of yoke 60 is offset transversely relative to the portion 61 so that the thrust force created on the yoke 60 by crank roller 56 will be applied through the center line of portion 61 so that the thrust will be direct and will not tend to create lateral forces, it being noted that the center line of portion 61 is in the same vertical longitudinal plane as the longitudinal center line of the bed 30.

The manner in which the Scotch yoke 60 is mounted on the frame 31 for longitudinal reciprocation is illustrated best in Figures 3 to 6. The yoke is supported by a horizontal bearing plate 63 which is illustrated in Figures 4 and 5. This plate 63 extends almost the full length of the frame 31 and is attached to the lower edges of the longitudinally extending tracks 39 and 40, as shown in Figures 3 and 6. The plate 63, as shown in Figure 5, comprises the two sections 64 and 65 which are at different levels, it being noted that the lower section 65 will be disposed towards the delivery end of the press. The section 64 carries on its upper face a roller bearing unit 66 which is of flat elongated form. Similarly, the section 65 carries the flat bearing unit 67. The bearing units 66 and 67 are offset transversely (Figure 4) to the same extent as the respective portions 61 and 59 of the yoke 60 with which they cooperate. Furthermore, due to the relative arrangement of the sections 64 and 65 of the plate, the bearing units 66 and 67 are offset vertically to the same extent as the respective cooperating portions 61 and 59 of the yoke 60. Thus, the yoke 60 is supported on anti-friction bearings for horizontal reciprocation. To prevent lateral or tilting movement of the yoke, longitudinal guides are provided at its upper and lower edges. The guide at the lower edge includes the upstanding longitudinal rib 68 (Figure 3) on plate 63 which extends upwardly into the longitudinal groove 69 formed in the lower edge of yoke 60. The upper guide includes an upstanding longitudinally extending rib or bar 70 which is rigidly secured to the upper portion of the track 40 at its inner side. This bar 70 extends downwardly into groove 71, formed on the upper edge of yoke 60, bar 70 being slidable in groove 71. Thus, yoke 60 is prevented from moving in any direction except lengthwise of the machine.

The rack bar 62 of yoke 60 engages a pinion 72, as shown best in Figures 1, 2, 5 and 6. This pinion 72 is keyed on a transverse hollow shaft 73 which is carried for rotation in bearings 74 and 75 (Figure 6) provided in the respective tracks 39 and 40 intermediate their upper and lower edges, it being noted that the pinion fits snugly in the bearings. Thus, reciprocation of the yoke 60 will oscillate the pinion 72 and thereby oscillate the shaft 73. The ends of the shaft 73 have keyed thereon the large bed moving gears 76 and 77. These gears engage with the respective racks 78 and 79 which are rigidly but removably secured to the lower side of bed 30 near the corresponding side edges of the bed.

The bed 30 is mounted for reciprocation on the longitudinally extending vertically disposed tracks 39 and 40, as previously indicated, and as shown best in Figures 3 and 6. The bed may be of any suitable construction and is provided with a pair of bearers 80 (Figures 1 and 2) at one end for cooperating with the pair of cylinder bearers 81 on the cylinder 32 and a pair of bearers 82 at the other end for cooperating with the bearers 83 of the cylinder 33. All of the bearers 80 and 82 are preferably

removably attached to the bed and have the tapered ends 84 (Figure 1) to facilitate moving of the cylinder bearers on and off such bed bearers, it being understood that the bearers function only during the printing stroke of the bed. The bed is further provided with the ink plates 85 and 86 (Figures 1 and 2) and suitable fastening members (not shown) for clamping the forms F thereto. With reference to Figure 3, it will be noted that the upper edges of the respective tracks 39 and 40 are provided with the longitudinally extending channels 87 and 88 in which bed supporting rollers 89 are disposed. At the inner side of the channels 87 and 88, the tracks 39 and 40 are provided respectively with the inwardly directed longitudinally extending lips 90 and 91. Gibs 92 and 93 are suitably attached to the lower surface of bed 30 and are provided with outwardly extending ledges 94 and 95 which overlap the lips 90 and 91. Thus, the bed can be moved longitudinally of the tracks 39 and 40 with little friction since it rests on roller bearings 89 and is held downwardly in position on said bearings by cooperation of the lips 90 and 91 with the ledges 94 and 95.

It will be noted that the bed driving pinion 72 and bed driving gears 76 and 77 will serve to drive the bed in a direction opposite to the direction of movement of the yoke 60. This is due to the fact that pinion 72 is located above yoke 60 and is an important feature since it serves to substantially counterbalance the horizontal forces created by the crank and yoke mechanism. It will also be noted from Figure 3 that the crank gear 50 extends down below the plate 63 which supports the yoke 60. This plate 63 is provided with an opening 96 through which this gear can project.

As previously indicated, the impression cylinders 32 and 33 are rotated in one direction at all times and in exact synchronism with the bed at all times. To accomplish this, the cylinders are driven from the bed by a variable speed drive which drives the cylinders in the same direction during the movement of the bed in both directions. This special cylinder drive is illustrated best in Figures 1, 2, 6, 7, 8, 9, 9a and 10.

With reference to Figure 6, it will be noted that the hollow shaft 73 has a shaft 97 extending therethrough and projecting from opposite ends. The ends of the shaft 97 are rotatably mounted in bearings 98 at the ends of hollow shaft 73. The left hand end of the shaft 97 (Figure 6) has keyed thereon a large driving sprocket 99 which is driven continuously by a chain 100 (Figure 1) that extends over a smaller sprocket 101 keyed on the constantly rotating flywheel shaft 44. The opposite end of shaft 97 has a beveled gear 102 keyed thereon. This gear 102 actuates the clutch mechanism of a cylinder driving unit indicated generally by numeral 103. This unit 103 is shown best in Figures 6 to 10.

With reference to Figures 7 and 8, it will be noted that unit 103 comprises a housing 104 made up of several sections joined together, as indicated, in an oil tight manner so that the housing can be filled with oil. At the inner side of housing 104 is the bed driving gear 77 which, as previously indicated, is keyed on the shaft 73 and will oscillate therewith. At the opposite side of the housing 104, a cylinder driving gear 105 is fixed thereon for rotation therewith. Also, directly within the gear 105, a gear 106 is supported for rotation on housing 104 by means of a bearing 107. The gear 106 oscillates exactly the same as gear 77 but in the opposite directions. Gear 106 is driven by a pinion 108 which is keyed on the outer end of a shaft 109. The shaft 109 is supported by a bearing 110 which is formed in track 40 adjacent its upper edge and by bearing 111 formed in the side frame member 36. The shaft 109 is driven by the oscillating pinion 112 which, in turn, meshes with the bed drive rack 79 that reciprocates with the bed 30. The housing 104 (Figure 8) is rotatably supported by a roller bearing 113 on the extreme end of shaft 73 and by roller

bearing unit 114 on an inwardly extending cylindrical portion 115 formed on the inner surface of a disc member 116. This member 116 covers an access opening in side support member 36 of the main frame 31 which permits access to the unit 103. Relative rotation between gear 77 and the gear 105 is possible because the latter is carried by housing 104 which can rotate relative to shaft 73 upon which the gear 77 is keyed.

The unit 103 includes a clutch arrangement for driving cylinders 32 and 33 in complete synchronism with the reciprocating type bed through gearing driven by the gear 105, as will be explained later. This clutch arrangement will serve to alternately drive the gear 105 from the gear 77 and the gear 106, it being understood that the gear 105 is always driven in the same direction. This clutch arrangement is illustrated best in Figures 7 to 10, inclusive. Gear 77 has a clutch ring 117 keyed on the hub thereof and this ring has inwardly projecting teeth 118 thereon. Gear 106 has a clutch ring 119 suitably secured thereto within the housing 104 and this ring has inwardly projecting teeth 120 thereon. (Figure 9). For cooperating with clutch ring 117, a ring 121 is provided which carries outwardly projecting teeth 122, this ring being splined for axial movement to the hub 123 of the housing 104. For cooperating with clutch ring 119, a ring 124 is provided and has outwardly extending teeth 125, this ring 124 being splined to the hub 126 of gear 105 which, in effect, is part of housing 104. Axial movement of rings 121 and 124 to alternately engage the respective rings 117 and 119 is accomplished with cam mechanism now to be described.

This mechanism comprises a series of cam units 127 (Figure 10) disposed angularly around the interior of the housing 104, three of these units being shown for illustration only. Each unit 127 comprises a cam disc 128 which is keyed on the inner end of a radially extending shaft 129. The shaft 129 is carried by a roller bearing 130 (Figure 8) at the outer wall of housing 104 and by a similar bearing 131 in a partition 132 spaced inwardly within the housing. The cam 128 (Figure 9) is provided with an outer flange which has a cam surface 133 formed on the inner surface thereof and an inner flange which has a complementary cam surface 134 formed on the outer surface thereof, the flanges projecting towards rings 121 and 124. These two cam surfaces 133 and 134 from a cam groove 135 which receives a cam follower roller 136 at one side and cam follower roller 137 at a diametrically opposed point. The roller 136 is carried on ring 121 and the roller 137 is carried on ring 124. The cam groove 135 is so shaped and the cam disc 128 is so driven that at the end of each stroke of the bed 30, the ring 121 is engaged with the ring 117 and the ring 124 is engaged with the ring 119. Upon further movement of the bed and the cam, one of the rings 122 or 124 will be moved out of engagement with its cooperating ring 117 or 119, this ring remaining out of engagement until just prior to the end of the bed stroke at which time it again engages with its cooperating ring.

To rotate the cam discs 128 about their axes, each of the radially extending shafts 129 carries a bevel pinion 138 keyed on the inner end thereof. All of these pinions 138 mesh with the driving bevel gear 102 (Figure 8).

The operation of the unit 103 is as follows: With the clutches in the condition shown in Figure 9, that is, with the pair of rings 117 and 121 out of engagement and with the pair of rings 119 and 124 in engagement, the gear 106 is clutched to the housing 104 and the gear 77 is free of the housing. At this time, the gear 77 will be driven in one direction by shaft 73, which is driven by rack pinion 72, and the gear 106 will be driven in an opposite direction by pinion 108 which is driven by the bed rack 79 through the medium of pinion 112 and shaft 109. This rotates gear 105 in the same direction as the gear 106 since the gear 106 is clutched to the housing 104 and

since gear 106 will rotate relative to gear 77. When clutch rings 117 and 121 are in engagement and rings 119 and 124 are out of engagement, the gear 77 is clutched to the housing 104 so that the gear 105 will be driven by the gear 77 in the same direction in which it is previously driven by the gear 106. The constant speed shaft 97 will drive the bevel gear 102 in the same direction as the housing 104. There will be a differential action between the two, because of the variable speed of housing 104, resulting in the gear 102 rotating relative to the housing 104 thereby rotating the pinions 138 about their axes and, in turn, rotating the cam discs 128 about the axes of the radial shafts 129. This will actuate the cam mechanism to cause operation of the clutches at the proper instance, as will be explained more in detail later. From the above, it will be apparent that the gear 105 is driven in the same direction at all times since it is alternately driven by the gears 77 and 106 which oscillate in opposite directions due to the movement of the bed 30 in opposite directions and to which the gears 77 and 105 are geared in the manner indicated.

As previously indicated, the gear 105, which is driven in the same direction at all times, serves to drive the cylinders 32 and 33. The driving mechanism between the gear 105 and the cylinders is shown best in Figures 1, 2, 6 and 14.

The cylinder drive from the gear 105 includes the gears 139 and 140 disposed on opposite sides of gear 105, as shown best in Figures 2 and 14. The gear 139 is provided with a spindle 141 which rotatably receives a sleeve 142 on the lower end of a link 143. On the sleeve 142 is rotatably disposed a sleeve 144 on the upper end of a link 145. The lower end of this link 145 is provided with a bearing 146 which is rotatably mounted on the hub 147 of the gear 105, as shown in Figures 8 and 14. The upper end of the link 143 carries a bearing 148 which receives the hub 149 of a cylinder drive gear 150 which is keyed to the shaft 151 of cylinder 32. The gear 105 drives the gear 139 which, in turn, drives the gear 150. Due to the provision of the linkage arrangement including the links 143 and 145, the gear 139 can rock about gear 105 and the gear 150 can rock about the gear 139. The gear 105 drives the gear 140 which, in turn, drives the cylinder drive gear 152 which is keyed on the shaft 153 of the cylinder 33. The mechanism for driving the cylinder 33 is provided with links 154 and 155 which are constructed and arranged similar to the links 143 and 145 so that the gear 140 can rock about the gear 105 and the gear 152 can rock about the gear 140. The supporting of the gears 139 and 150 at the one side of the gear 105 and the gears 140 and 152 at the opposite side of the gear 105 for rocking movement is important, as will later appear, to permit the necessary vertical movement of the cylinders 32 and 33 without interfering with the driving connections to such cylinders. It will be noted that the cylinders 32 and 33 will both be rotated in the same direction.

The manner in which the cylinder shafts 151 and 152 are supported is illustrated best in Figures 1, 2, 11, 12, 14 and 17. The manner in which the cylinder 32 is supported will be described in detail and it will be understood that the cylinder 33 is supported in an identical manner. The end of the shaft 151 opposite to where the gear 150 is mounted is rotatably disposed in an eccentric bearing 156 (Figures 11 and 12) which is carried at the upper edge of the side frame member 35. The eccentric 156 is rotatably disposed in a bearing formed by cooperation of a half bearing member 157, that is integrally formed on the upper portion of side member 35, with a cap member 158 that is bolted on the member 157. The gear end of the shaft 151 is similarly mounted in an eccentric 159 (Figure 6) and carried by a half bearing member 160 provided on the upper edge of side frame member 36 which has a cap member 161 bolted thereto. The shaft 151 extends outwardly through the bearing at this side

and carries the gear 150 previously mentioned. The cylinder 33 is supported in exactly the same manner, the shaft 153 (Figures 11 and 17) being rotatably disposed in an eccentric 162 at the one end and by a similar eccentric 163 at the opposite end. Thus, each cylinder is supported by a pair of rotatable eccentrics. In one rotative position of each pair of eccentrics, the cylinder bearers will bear against the bed bearers, for example, the bearers 31 (Figure 6) of cylinder 32 will bear against the bed bearers 80. In another position of the pair of eccentrics, the cylinder which they carry will be moved upwardly away from the bed and the cylinder bearers will not contact the bed bearers.

The mechanism for moving the cylinders vertically is illustrated best in Figures 6, 11 and 12. This mechanism is such that it will function to lift the impression cylinders 32 and 33 away from the bed after the printing stroke just as the cylinders bearers run off the bed bearers.

This mechanism comprises a rack bar 164 which is reciprocably mounted at the operator's side of the machine, as shown in Figure 6, and in substantial alignment with the cam 54. The bar 164 is slidably mounted (Figure 11) in bearing members 165 and 166 which extend through openings in the transverse frame beams 41 and 42, the members 165 and 166 being bolted to the side frame member 35. It will be apparent from Figure 12 that member 165 has a recessed upper edge 167 which receives the rack bar 164, the bearing member 166 being similarly formed and, thus, preventing lateral movement of the bar 164. The cam 54 (Figure 11) is provided with a cam groove 168 on its inner side which receives a cam follower roller 169. This roller 169 is carried by a gear segment 170 which is rockably mounted on a transverse pin 171 that is mounted on the side member 35 (Figures 11 and 13). The teeth on the upper portion of the segment 170 engage rack teeth 172 on the lower surface of bar 164, a thrust bearing 173 being provided substantially above this point of engagement. This bearing 173 is provided with a grooved lower edge in which the upper edge of the bar 164 slidably fits. This bearing 173 is bolted to the side frame member 35. The cam groove 168 is so shaped that the gear segment 170 is rocked about the pin 171 at the proper times to move the rack bar 164 to the desired extent in the proper direction.

The rack bar 164 is provided on its upper surface with two sets of rack teeth 174 and 175 which are spaced longitudinally thereof substantially corresponding to the spacing of cylinders 32 and 33. These sets of teeth 174 and 175 engage the respective rack pinions 176 and 177 which are rotatably carried on the transverse shafts 178 and 179. Each of the pinions 176 and 177 forms a part of a clutch which includes a shiftable member 180 (Figure 12) that is keyed to its respective shaft. The shafts 178 and 179 extend from one side of the machine to the other beneath the bed 30 and the respective cylinders 32 and 33 being disposed within recesses in the beams 41 and 42 and being rotatably mounted in bearings at the ends thereof, such as bearing 178a in Figure 12. On each end of the shaft 178 an eccentric 181 is keyed while on each end of the shaft 179 an eccentric 182 is keyed, the eccentrics at one end only of the shafts being shown. The eccentrics 181 are associated with link units 183 and the eccentrics 182 are associated with link units 184. The units 183 serve to operatively connect the eccentrics 181 to the cylinder supporting eccentrics 156 and 159 which support the cylinder 32 while the link units 184 connect the eccentrics 182 to the eccentrics 162 and 163 which support the cylinder 33. Each of the units 183 and 184 is adjustable as to length, being composed of a lower bearing section 185 which has a bearing portion on its lower end that rotatably receives the eccentric carried by the transverse shaft and an upper section 186 which is pivoted at 187 to a radial extension on the cooperating cylinder supporting eccentric. The sections 185 and 186 are connected to

gether by means of a screw member 187a which has right and left hand threads in order to obtain a turnbuckle effect. Each of the link units 183 and 184, therefore, can be adjusted to change its effective length so as to initially set the cylinder-supporting eccentrics accurately in order to set the cylinders to obtain the proper impression on the type form carried by the bed.

It will be apparent that the cylinder lifting and lowering mechanism will function as follows: The cam groove 168, upon rotation of cam 54, will produce rocking of segment 170 which will slide the rack bar 164 longitudinally. This will rotate both of the rack pinions 176 and 177 about the axes of shafts 178 and 179. If the clutch members 180 are engaged with the pinions, the shafts 178 and 179 will be rocked. This will, in turn, rock the eccentrics 181 and 182, thereby rocking the eccentrics which support the cylinder 32 and those which support the cylinder 33. Rocking of the cylinder supporting eccentrics will produce vertical movement of the cylinders 32 and 33 relative to the bed 30. The clutch members 180 will be controlled by the usual type of cylinder trip mechanism (not shown) which is well known in the art.

Vertical movement of the cylinders 32 and 33 will not interfere with the drive to the cylinders since gears 150 and 152 rock about the respective gears 139 and 140 and these latter gears rock about the driving gear 105.

The transfer unit 34 is illustrated best in Figures 15 to 28. This mechanism is adapted to transfer the sheets, after being printed on cylinder 33, to the cylinder 32 in exact registry so that the cylinder 33 can print one color and the cylinder 32 another. The unit 34 is disposed between the two cylinders as shown in Figures 1, 2, 15 and 17. It moves vertically with the cylinder when they are moved towards and away from the bed.

The unit 34 includes the side frame members 188 and 189 (Figures 17 and 18) which extend longitudinally. These members are joined together by transverse hollow tie rods 190 and 191 disposed intermediate the ends of the frame members and by solid transverse rods 192 and 193 (Figure 15) disposed adjacent the ends of the side members 188 and 189. The frame of the transfer unit is supported by means of the eccentrics 156 and 159, which support cylinder 32, and the eccentrics 162 and 163 which support the cylinder 33. To support the frame of the transfer unit from the eccentrics 156 and 159, the arms 194 and 195 (Figures 17 and 18) are provided which extend downwardly from the side members 188 and 189 and towards the axis of the cylinder 32. The arm 194 is provided with a bearing portion 196 on its lower end which rotatably fits on the eccentric 156 while the arm 195 is provided at its lower end with a bearing portion 197 which rotatably fits on the eccentric 159. To support the transfer frame from the eccentrics 162 and 163, the arms 198 and 199 are formed at the opposite end of the frame and project downwardly and towards the axis of the cylinder 33. The lower end of each of these arms 198 and 199 is provided with a yoke portion 200 (Figure 15a), which engages the respective eccentric 162 or 163. Pivoted to the yoke portion 200 is the arcuate locking member 203. The member 203 may be normally retained in position by bolt members 205. Each of these bolt members is pivoted at 206 to the yoke part of the arm and is swingable into and out of a notch 207 in the locking member.

With this arrangement, the entire transfer unit can be swung upwardly out of the way to permit make-ready and access to the inkers I which will be disposed between the cylinders 32 and 33 and is shown diagrammatically in Figures 1 and 15. To permit this, the bolts 205 will be released and the feed end of the unit 34 can be swung upwardly, the arms 194 and 195 at the opposite end pivoting about the axes of the eccentrics 156 and 159.

As previously indicated, the side frame members 188 and 189 are connected together by the transverse mem-

bers 190, 191, 192 and 193. Each of the members 190 and 191 is connected at each end to the corresponding side plate by means of a socket or boss 208 (Figure 17) in which the end of the rod fits and in which it is pinned. The rods 192 and 193 are carried by the side plates 188 and 189 in the manner shown in Figure 18 which shows the rod 192, it being understood that the rod 193 is similarly mounted. It will be noted from Figure 18 that the cylinder drive gear 150 meshes with a gear 209 which is rotatably mounted within a sleeve portion 210 formed on the side frame member 189. The gear 209 is keyed to the hub 211 of a sprocket 212, the hub 211 being disposed within a bearing 213 mounted in the sleeve portion 210. Thus, the gear 209 and the sprocket 212 will rotate as a unit. Disposed within the hub 211 of sprocket 212 is an eccentric 214, roller bearings 215 being provided between the eccentric and the hub. The end of the rod 192 is keyed within an eccentric opening in the member 214. The opposite end of the rod 192 is keyed eccentrically within the eccentric member 216 which is keyed within an opening 217 formed in the side frame member 188. Rotatably mounted on the eccentric 216 by roller bearings 218 is a sprocket 219. The rod 193 is mounted at the opposite end of the unit 34 in exactly the same manner. As shown in Figures 15 and 17, at the opposite end of the unit 34, a similar sprocket and gear arrangement is provided. At that end, the cylinder drive gear 152 drives a gear 220 which is keyed on a sprocket 221. This sprocket 221 is at one end of the rod 193. At the opposite end of the rod 193, the sprocket 222 is provided. The sprockets 212 and 221 carry a longitudinally extending endless chain 223 while the sprockets 219 and 222 carry a longitudinally extending endless chain 224.

In order to drive the sprocket 219 from the sprocket 212, the arrangement shown in Figure 18 is provided. The sprocket 212 has an internal gear 225 formed therein. This gear meshes with a set of gear teeth 226 on a pinion 227 which is keyed on a hollow shaft 228 that is disposed on the rod 192. The shaft 228 is rotatably mounted on the rod 192 by means of the bearings 229 and 230. The opposite end of the shaft 228 has a pinion 231 keyed thereon. A set of teeth 232, formed on this pinion 231, engage an internal gear 233, formed within the sprocket 219. Thus, sprocket 212 will rotate with driven gear 209 and this will rotate shaft 228, through the medium of internal gear 225 and pinion 227, which, in turn, will drive sprocket 219, through the medium of pinion 231 and internal gear 233. A similar arrangement is provided for driving the sprocket 222 from the sprocket 221. Thus, each pair of sprockets at each end of the transfer unit is positively driven and the chains 223 and 224 are not relied upon as driving connections.

The chains 223 and 224 are relied upon merely to transfer the sheet from cylinder 33 to cylinder 32 and registering mechanism is associated therewith to insure accurate registry of the sheet as it is transferred from cylinder 33 to cylinder 32. In order to accomplish this transfer of the sheet from the one cylinder to the other, the chains 223 and 224 carry a transversely disposed gripper bar unit 234. This gripper bar unit 234 is shown best in Figures 15, 17 to 25.

The gripper bar unit includes the transversely extending gripper pad shaft 235 (Figures 15 and 17) and the transversely extending gripper shaft 236 which is disposed directly forward of the shaft 235. The shafts 235 and 236 are mounted on chain 223 in the manner shown in Figures 24 and 25. The end of the shaft 235 fits into a socket 237 formed in a bracket 238. This bracket 238 is rigidly attached to a plate 239 which is the inner side of a link of the chain 223. The bracket 238 is provided with the bearings 240 and 241 in which the end of the shaft 236 is rockably mounted. Between the bearings 240 and 241 a rocker arm 242 is keyed to the shaft 236. This rocker arm on its outer end carries a cam follower roller 243. A spring 244 is associated with the

rocker arm 242 and normally urges it upwardly, as indicated by the dotted lines in Figures 25. When the rocker arm is forced into its lowermost position, as shown in Figure 24, the roller 243 is moved into a recess 245 formed at the top side of the bracket 238. The bracket 238 is provided with a gear segment 246 on its upper side and gear segment 247 on its lower side, as indicated best in Figures 15 and 25.

The opposite ends of the shaft 235 and 236 are supported by chain 224 in the manner shown in Figures 22 and 23. From these figures, it will be noted that the shaft 235 fits in a socket 248 which is carried by a bracket 249. This bracket is rigidly attached to a plate 250 which is the inner side of a link of the chain 224. The shaft 236 is rockably mounted in a bearing 251 formed as a part of the bracket 249. This bracket 249 also has a gear segment 252 formed on its upper side and a gear segment 253 formed on its lower side.

The transverse shaft 235 carries the gripper pads 254 (Figure 17), which are disposed at axially spaced intervals. At the same spaced intervals the shaft 236 carries the grippers 255 which cooperate with the pads 254. It will be apparent that when the shaft 236 is rocked by means of the rocker arm 242 (Figures 26 to 28), the grippers 255 swing about the axis of the shaft 236 and relative to the gripper pads 254.

For swinging the rocker arm 242 to rock the gripper shaft 236 at the proper times, we provide a cam arrangement. This cam arrangement is adapted to rock the gripper shaft 236 when it is adjacent the cylinder 33 to bring the grippers 255 into contact with the pads 254 and to rock the gripper shaft 236 when it is adjacent the cylinder 32 to swing the grippers 255 away from the pads 254. This cam arrangement includes a cam member 256 (Figure 35) which is at the delivery end of the unit 34 and a cam member 257 which is at the receiving end thereof. These cams are located at the plate 189 and are bolted thereto. The cam 256 will engage the roller 243 as the gripper bar unit 234 is carried about the sprockets 212 and 219 by the chains 223 and 224. The cam 257 is so located that it engages the roller 243 as the gripper bar unit 234 is carried around the sprockets 221 and 222 by the chains.

It will be understood that the cylinders 32 and 33 are provided with the usual grippers and gripper pads and with the usual means for operating them. In Figures 26 to 28, we have illustrated the cylinder 33 provided with the pads 260 and with the cooperating grippers 261. The operating mechanism for the grippers 261 will serve to swing the grippers relative to the pads to open and close the grippers at the proper times. It will be understood that the transfer grippers 255 are staggered relative to the cylinder grippers 261, as shown best in Figure 18.

In order to obtain exact registry of the sheet when it is transferred from the cylinder 33 to the cylinder 32, we provide special mechanism for registering the gripper bar unit 234 in all directions relative to the cylinder 33 at the point of transfer of the sheet from the cylinder to the gripper bar and relative to the cylinder 32 at the point of transfer of the sheet from the gripper bar to the cylinder 32.

This mechanism includes a cam arrangement shown in Figures 18 to 20 which accurately positions the gripper bar unit 234 axially at the instant of transfer of the sheet from the cylinder 33 and at the instant of delivery of the sheet to the cylinder 32. This cam arrangement comprises a cam 262 (Figures 18 and 19) which is bolted to the side frame member 188 at the lower side thereof adjacent the cylinder 32. Another identical cam (not shown) is bolted to the frame member 188 at the lower side thereof and adjacent the cylinder 33. For cooperating with these cams, a roller 264 (Figures 18, 19, 20, 22 and 23) is carried by the side plate 265 of the link of chain 224 that includes plate 250. As the gripper bar 234 moves around the sprockets 221 and 222 towards

the cylinder 33, the roller 264 enters the cam groove of the cam 263 and the gripper bar is registered laterally with the cylinder 33. As the gripper bar 234 starts to move upwardly around the sprockets 212 and 219, the roller 264 enters the groove of the cam 262 and the bar 234 is registered laterally with the cylinder 32.

For registering the gripper bar accurately circumferentially of the cylinder 33 during transfer of the sheet therefrom and for registering the gripper bar circumferentially relative to the cylinder 32 during delivery of the sheet from the transfer unit to the cylinder, we provide the means which is shown best in Figures 15, 17, 18 and 21. This means includes the arcuate racks 266 and 267 (Figure 17) carried on opposite ends of the cylinder 32 and arcuate racks 268 and 269 carried on opposite ends of the cylinder 33. The racks 266 and 268 will cooperate with the gear segment 247 formed on the lower side of the bracket 238 at the end of the gripper bar 234. The racks 267 and 269 will cooperate with the gear segment 253 formed on the lower edge of the bracket 249 at the opposite end of the gripper bar.

The gear segment 246 formed on the top edge of the bracket 238 will cooperate with a set of gear teeth 270 (Figures 15 and 18) on the pinion 227 which is mounted on shaft 228 that is carried by rod 192. The registering segment 246 also cooperates with the teeth 270a of a pinion 227a which is mounted on shaft 228a that is carried by rod 193 like the pinion 227 which is carried by shaft 228 mounted on the rod 192.

The top segment 252 on the bracket 249 at the opposite end of the gripper bar 234 will cooperate with a set of teeth 272 (Figure 18) on the pinion 231 which is associated with rod 192 and with the equivalent set of teeth on the pinion 231a that is keyed to shaft 228a mounted on rod 193.

To compensate for any deflection which might occur at the center of the gripper bar 234, registering means is provided at the center of such bar. This means comprises a bracket 274 (Figures 17 and 21) which is provided with an opening 275 through which the shaft 235 passes and with an opening 276 through which the shaft 236 passes. The top of this bracket 274 has a gear segment 277 formed thereon. This gear segment 277 will cooperate with a pinion 278 which is keyed to shaft 228 and with a pinion 278a which is keyed to shaft 228a. The lower edge of the segment is provided with a cylindrical bearing surface 279 which cooperates with a member 280 that is similar to the cylinder gripper pads 260. It will be understood that one of these members 280 will be located on each cylinder and will be mounted in the same manner as the cylinder gripper pads but will not have the cylinder grippers 261 associated therewith.

In the operation of this registering mechanism for registering the gripper bar 234 circumferentially relative to the cylinders, it will be noted that as the chains 223 and 224 carry the bar 234 around the sprockets 221 and 222, the gear segments 246 and 252 will gradually approach and eventually mesh with the respective gear teeth of the pinions 227a and 231a. At the same time the segments 247 and 253 will approach and mesh with the racks 268 and 269 on the cylinder 33. Also, at this time the segment 277 on bracket 274 will approach and engage the pinion 278a carried by shaft 228a. Thus, a registering arrangement is provided at each end of the gripper bar 234 and intermediate its ends. This will ensure exact registry of the bar 234 with the cylinder 33 at the instant of transfer of the sheet from the cylinder to the gripper bar. Similarly, when the gripper bar 234 moves to the other end of the transfer unit adjacent the cylinder 32 and starts to move upwardly around the sprockets 212 and 219, the lower gear segments 247 and 253 will approach and engage the racks 266 and 267 carried on the cylinder 32. At the same time the upper gear segments 246 and 252 will gradually approach and engage

the teeth 270 of pinion 227 and the teeth 272 of pinion 231. Simultaneously, the segment 277 of the intermediate bracket 274 will gradually approach and engage the pinion 278 and at this instant, the surface 279 will be in contact with the member 280 carried by that cylinder. Thus, these registering devices at the ends of bar 234 and intermediate the ends will function to cause exact registry of the sheet as it is transferred from bar 234 to the cylinder 32. The teeth of the various cooperating registering devices are so shaped and arranged that they are tightly in mesh only at the instant of sheet transfer.

The function of the transfer unit 34 in transferring the sheet S from the cylinder 33 is illustrated in Figures 26 to 28. As the cylinder 33 rotates in the direction indicated the transfer bar 234 will be moved in the direction indicated and will be approaching the cylinder. The sheet S (Figure 28) will at this time be gripped between the cylinder grippers 261 and the pads 260. The transfer grippers 255 will be spaced from the transfer gripper pads 254. As the bar 234 continues to move, the grippers 255 will be rocked into engagement with the pads 254, as shown in Figure 27. As the gripper bar 234 continues to move and the cylinder 33 continues to rotate, the cylinder grippers 261 are rocked away from the cylinder gripper pads 260 to free the sheet and complete its transfer to the bar 234. At this instant, the registering devices have functioned to cause the gripper bar 234 to register exactly with the cylinder 33. The sheet will now be carried by the transfer bar over a plate or web 281 (Figure 15) which is provided between the side plates 188 and 189 at the lower edges thereof and which extends between the two cylinders. As the gripper bar 234 approaches the cylinder 32, the various registering devices will function in the manner previously indicated and the gripping means on the bar and the cylinder will function in the same manner as illustrated in Figures 26 to 28 but in a reverse order so as to transfer the sheet from the bar 234 to the cylinder 32.

In order to compensate for wear of the chains 223 and 224, means is provided for taking up this wear as shown in Figures 15 and 16. This means is associated with each of the chains but in Figures 15 and 16 we have illustrated the means associated with the chain 223. This means comprises a bracket 282 which has a bearing member 283 formed on its inner edge that bears against the top flight of the chain. This bracket 282 is mounted on the side frame member 189 by means of bolts 284 passing through vertical slots 285. As the chain wears and tends to become looser, the bracket 282 may be adjusted downwardly. A similar bracket 286 is provided at the lower side of the frame member 189 and is provided with a bearing member 287 which engages the lower side of the lower flight of the chain. This bracket 286 may be adjusted upwardly as the chain wears. An identical double bracket arrangement is associated with the other chain 224 and is mounted on the frame member 188 to compensate for wear of such chain.

With reference to Figure 2, a suitable feedboard arrangement, illustrated diagrammatically at 290 will be provided for feeding the sheets S to cylinder 33 and a suitable delivery mechanism, illustrated diagrammatically at 290a, will be provided for taking the sheets from the cylinder 32. The delivery mechanism is driven by cylinder gear 150 as shown. The feed from feedboard 290 to cylinder 33 will occur just as the cylinder 33 comes to a stop. Similarly, the delivery of the sheet from cylinder 32 to the delivery mechanism 290a will occur just as cylinder 32 comes to a stop.

The operation of the entire press will now be described. As previously indicated, the bed 30 is reciprocated with a full harmonic motion. As the crank gear 50 rotates, the roller 56 moves vertically in the slot 58 and reciprocates the yoke 60 on the bearings 66 and 67 which support it. The bed-driving pinion 72 is oscillated by means

of the rack 62 on the yoke 60. Oscillation of the pinion 72 produces oscillation of the shaft 73 which carries the gears 76 and 77 that engage the bed racks 78 and 79. Consequently, the bed is also reciprocated. We have located the pinion 72 above the yoke 60 and the rack bar 62 carried thereby, so that when the yoke 60 is moving in one direction, the bed 30 is moving in the opposite direction. Because of this opposed movement, a substantial balancing effect is obtained which greatly reduces the effects of the forces of acceleration and deceleration of the bed produced by the crank mechanism and makes it unnecessary to bolt the press to the floor. Furthermore, we have designed the member 60 with the portion 59 offset relative to the portion 61 so that the thrust force applied by roller 56 through the yoke 60 will be applied directly through the center line of the main part of the yoke. It will be noted from Figure 1, that the crank gear 50, the yoke 60, and the bed driving gears 76 and 77 are all arranged symmetrically relative to the sides of the press which evenly distributes the forces transversely of the machine and enhances the balancing effect. As stated above, the bed motion is a full harmonic motion. In Figure 2, the crank roller 56 is shown in dead-center position. As the crank gear 50 rotates clockwise, the movement of the bed starts and increases in speed until the roller 56 moves through 90° , at which time the speed of the bed starts to decrease until the roller moves through another 90° when the bed will be stopped. Continued movement of the crank gear and roller will start the bed in a reverse direction, causing it to pick up speed as the roller moves through another 90° and decrease in speed and finally stop as the roller moves through the final 90° .

Rotation of the cylinders 32 and 33 is fully synchronized with the full harmonic bed movement described above. This is accomplished by having the cylinder drive gear 105 under the control of the gear 77 or the gear 106 at all times. Since the gears 77 and 106 are geared indirectly to the bed driving pinion 72 and are oscillated thereby, there is never any question of the gears being out of synchronism with the bed motion. As pointed out above, the gear 77 will be oscillated since the shaft 73 is oscillated by the pinion 72 which is engaged by rack 62 carried by yoke 60. The gear 106 will also be oscillated but it will always turn in a direction opposite to that in which the gear 77 is turning. This is due to the pinion drive, including pinion 108, which is disposed between the bed rack 79 and the gear 106. Although the gears 77 and 106 are oscillated, the cylinder driving gear 105 is always rotated in the same direction. This is accomplished by having the clutch arrangement whereby the gear 105 is alternately driven by the gears 77 and 106, the gear 105 being driven by gear 77 when it is rotating in the counterclockwise direction (Figure 2) and being driven by gear 106 when it is rotating in the clockwise direction, causing the gear 105 to rotate in a counterclockwise direction at all times. The cylinder drive gear 105 must be under positive control at all times and, therefore, the clutch arrangement is such that the gear 105 will always be connected either to gear 77 or gear 106, and at times to both. Before it is disconnected from one gear, it is connected to the other. The clutch mechanism will function to disconnect the gear 105 from one of the gears 77 and 106 and connect it to the other at the end of each stroke of the bed while the bed is substantially stationary. This is accomplished with the differential arrangement incorporated in the cylinder drive unit 103.

Assuming that the gear 77 is clutched to housing 104 and will, therefore, drive the gear 105, and that the bed is stationary, it will be apparent that movement of the bed 30 from the extreme right-hand position (Figure 2) towards the left by the crank drive will also rotate the housing 104 in a counterclockwise direction. As the bed starts to move, it picks up speed and the housing 104

rotates at correspondingly increasing speed. However, the clutch-actuating bevel gear 102 is constantly driven at a fixed speed and in a counterclockwise direction and during most of the stroke of the bed this speed is greater than the speed of rotation of the housing but at a certain period, the speed of rotation of the housing is greater than that of the gear 102. At any time that the speed of rotation of gear 77, and consequently housing 104, differs from the speed of rotation of gear 102, the pinions 138 will revolve around the gear 102 in one direction or the other to compensate for this speed differential and, therefore, will rotate the cam discs 127. The ratio of the gear 102 to the pinions 138 is selected so that during one complete cycle (that is two strokes of the bed) the pinions 138, and, consequently, the cam discs 127 will be driven through one complete revolution by the differential action causing the pinions to revolve around the gear 102. For example, the ratio of the gear 102 to the pinions 138 may be three to one, the housing 104 will rotate through $1\frac{1}{3}$ revolutions for each cycle of the bed movement, and the gear 102 will rotate in the same direction as housing 104 through a $1\frac{2}{3}$ revolutions during each cycle of the bed movement. This leaves a differential of $\frac{1}{3}$ between the revolutions of the housing 104 and the gear 102 and since the gear 102 has a 3 to 1 ratio with pinions 138, the result will be that each of the cam discs 127 will be rotated through one complete revolution during each cycle of the bed movement. Consequently, just after the bed reaches the end of its stroke in traveling from right to left, the cam discs will have completed a half-revolution which will engage the clutch of gear 105 before the clutch of gear 77 is disengaged. As the bed starts to move to the right, the clutch of gear 77 is disengaged. This will now cause the gear 105 to be driven by gear 106, since the gear 106 will be clutched to housing 104. As the bed continues to move to the right through another stroke, each of the cam discs 127 will be rotated through another half revolution.

The action of each cam disc 127 is illustrated best in Figures 9 and 9a. When the rollers 136 and 137 (Figure 9a) are both in the concentric part A of the cam groove 135, both clutches are in engagement. This occurs at the end of each stroke and at the completion of each one-half revolution of the cam. Assuming that the cam disc is rotated in a counterclockwise direction, the roller 137 will move into the flattened part B of the cam groove, while the roller 136 will still be in the concentric part A of the groove. The movement of roller 137 from part A of the cam groove to part B of the cam groove disengages clutch ring 124 from clutch ring 119. However, as long as roller 136 remains in concentric part A of the cam groove, the clutch ring 121 will remain in engagement with clutch ring 117. Before roller 136 passes out of one end of the concentric part A of the cam groove to disengage ring 121 from ring 117, the roller 137 passes into the other end of the concentric part A of the groove, to engage ring 124 with ring 119. Thus, one clutch is always engaged before the other is disengaged. It will be apparent that with each half-revolution of the cam disc, one clutch remains in engagement while the other clutch becomes disengaged and remains out of engagement for the major portion of the half-revolution and is again engaged just prior to the completion of the half-revolution.

In Figure 29, we have illustrated schematically the relative positions of the main crank 50; the cams 128; and the housing 104. The outer circle represents the main crank; the next inner circle represents the cams; and the innermost circle represents the housing. It is understood that the movement of the housing, the surfaces of the cylinders 32 and 33, and the bed are equal at all times. The successive angular positions of each of these members during certain periods in the cycle of operation of the press is indicated by successive letters, the same letters on the respective circles indicating corresponding positions

of these members at any particular instant during the cycle.

For example, as the main crank rotates from dead-center or zero position to position *a*, the cam rotates through a greater distance to its position *a* and the housing rotates a minute amount to its position *a*. The successive positions of all of these members are indicated by successive letters. It will be noted that when the main crank and housing move from position *e* to position *f*, the cam reverses its direction of rotation and this reversing is continued until position *g* is reached when it again reverts to its original direction of rotation. The rotation of the cam in the first indicated direction occurs at the time the gear 102 is rotating faster than housing 104. The reversing of the cam occurs when the housing 104 travels at a faster rate than the gear 102 which is at the time the bed approaches and reaches its maximum speed. The successive positions of all these members is indicated, position *i* being the last-indicated, which will be the position they occupy after the crank has rotated through 180°. Thus, the effective rotation of the cam is 180° for each 180° rotation of the main crank and the housing gear rotates $\frac{1}{2}$ of a revolution for each 180° rotation of the main crank.

It will be apparent from the above that the cylinder drive gear 105 is rotated in the same direction at all times and in complete synchronism with the bed movement. This cylinder drive gear 105 will, therefore, drive the cylinders 32 and 33 so that the rotation of the cylinders will always be in complete synchronism with the movements of the bed. Consequently, during the printing stroke of the bed, the surface of each cylinder will move at the same speed as the cooperating printing form and, therefore, a proper impression will be obtained. As previously indicated, the cylinders are driven from the gear 105 through the medium of idler gears 139 and 140 and cylinders gears 150 and 152, the cylinders being driven in the same direction.

The cylinders 32 and 33 are lifted from the bed during the return stroke of the bed and are lowered onto the bed during the printing stroke thereof. The vertical movement of the cylinders is brought about by the rotation of the cam 54. Rotation of the cam produces rocking of the gear segment 170 which moves the rack bar 164 longitudinally. This rotates the eccentrics 181 and 180 through 180° and thereby moves the tie rods 183 and 184 vertically and rocks the eccentrics 156 and 159, which support the cylinder 32, and rocks the eccentrics 162 and 163 which support the cylinder 33. The shape of the cam groove 168 is such and the speed of rotation of the cam is such that the cylinders are lifted from the bed after the completion of the printing operation and prior to the beginning of the return stroke of the bed. Vertical movement of the cylinders 32 and 33 will not interfere with the cylinder drive since the gears 150 and 152 can rock around gears 139 and 140 and these latter gears can rock about the gear 105.

The transfer unit 34 is driven continuously by means of the cylinder gears 150 and 152 meshing with the respective gears 209 and 220 of the transfer unit. This transfer unit will also move vertically with the cylinders since the frame thereof is carried by the eccentrics 156, 159, 162 and 163 which support the cylinders. The transfer unit 34 will serve to transfer the sheet from cylinder 33 to cylinder 32 in exact registry and without any contact with the printed surface of the sheet. The registering means on the transfer unit will cooperate with the registering means on the cylinders to obtain exact registry of the sheet in all directions.

In Figure 30, we have illustrated how the press can be modified to use more than two cylinders. In this example, we have illustrated four cylinders but it is to be understood that any desired number can be used depending upon the number of colors to be printed. In this press, the cylinders 32a and 33a are equivalent to the

cylinders 32 and 33 of the other press. A transfer unit 34a, like the unit 34, is disposed between the cylinders 32a and 33a. Another pair of cylinders 32b and 33b is illustrated. Between the cylinders 32a and 32b, a transfer unit 34b will be provided while between the cylinders 33b and 32b a transfer unit 34c will be provided. The cylinders 32a and 33a will be driven in exactly the same manner as the cylinders 32 and 33 by means of cylinder gears 150a and 152a, idlers 139a and 140a, and the main cylinder drive gear 105a. This gear 105a will be driven by a cylinder drive unit like the unit 103. The gear 105a will drive an idler 310 which will mesh with a gear 105b. This gear 105b will drive the cylinders 32b and 33b through the medium of idler gears 311, gear 105c, gears 139b and 140b, and gears 150b and 152b. The transfer unit 34a will be driven in exactly the same manner as the unit 34, the gears 150a and 152a of the cylinder drive meshing with the gears 220a and 209a of the transfer unit. The gears 209b and 220b of the unit 34b are driven by the gears 152a and 150b while the gears 209c and 220c of the unit 34c are driven by the gears 150b and 152b. All of the parts of this four-color press will correspond to the similar parts of the two-color press. A single bed 30a will be used and it will have the four forms for cooperating with the respective cylinders. This bed will be moved like the bed 30 by means of yoke 60a that carries rack 62a which meshes with pinion 72a, the yoke being supported on plate 63a.

It will be understood from the above description that we have provided a two-revolution flat-bed and cylinder printing press with full harmonic bed motion and with the surface of the printing cylinder or cylinders perfectly synchronized with the movement of the type bed at all times. The means for reciprocating the type bed is so designed and constructed as to substantially counterbalance the forces of acceleration and deceleration created by the reciprocation of the type bed, so that the press will not move on the floor even when operated at speeds substantially greater than the maximum speeds of existing flat-bed presses without bolting the press to the floor or embedding it in concrete. Furthermore, the mechanism for reciprocating the type bed is symmetrically arranged which enhances the counterbalance effect. Our press can be operated at speeds far in excess of those of conventional flatbed presses without injury to the sheets of paper being fed into the press because the cylinder or cylinders on our press take the sheets from the feed-board at or near the end of one stroke of the bed when the cylinder or cylinders are stopped or almost stopped. Delivery from the last cylinder to the delivery unit also occurs at or near the stop point. With our press, it is possible to have a smaller diameter cylinder. We have so designed our press that the mechanism for moving the bed and cylinder or cylinders is so located that it will not interfere with reinforcement of the main frame directly under the locations where the printing impressions are taken, a feature which is so necessary for the required rigid impressions. In our press, the means for raising and lowering the printing cylinder or cylinders is operated directly underneath the type bed and is, therefore, much more simple and compact and has far more rigidity than prior art arrangements, which latter extend practically to the floor. The means for driving the printing cylinder or cylinders is completely under the control of the bed-driving means on both strokes of the bed, and it is not necessary, as with prior art presses, to lift the cylinder driving gears partly out of mesh, which results in excessive play or back-lash and noisy operation, the gears on our press remaining in full mesh, even when the cylinder or cylinders are raised to permit passing of the form or forms on the return stroke of the bed. Our two-revolution cylinder printing press with full harmonic bed motion can be provided with a plurality of impression cylinders cooperating with a plurality of forms on a single reciprocable type bed so as to render the press suitable for

multi-color work. In the multi-color press, according to our invention, the cylinders are spaced apart sufficiently so that an inker can be located relative to each cylinder in a position identical with the position of the inker in a single-color press, with which practically all operators are familiar. The transfer mechanism can be moved away from the cylinders to permit access to the inker disposed between two adjacent cylinders. The transfer mechanism is so constructed that exact registration with the cylinders, in all directions, will be accomplished so that each sheet will be transferred from one cylinder to the next in absolute register. This accurate registration is obtained even though chains are used, since the chains merely move the gripper bar between its various positions, registration being accomplished independently of the chains. Furthermore, during transfer, the sheet is always flat and nothing touches the printed side thereof. Thus, heavy cardboard can be printed and transferred without damage thereto, because it is not necessary to bend the cardboard around a transfer cylinder, as in prior art two-color presses. Also, since nothing touches the printed side of the sheet during transfer, smearing or smudging cannot occur.

Various other advantages will be apparent.

Having thus described our invention, what we claim is:

1. A flat bed and cylinder printing press comprising a reciprocable bed and a rotatable cylinder disposed in cooperative relationship, means for reciprocating said bed with a full harmonic motion, said means comprising a rotatable crank, a reciprocable rack driven by the crank, gearing connecting the rack to the bed for reciprocating the bed, means for driving the cylinder in one direction only at all times through two complete revolutions and so that the peripheral speed thereof coincides with the speed of movement of the bed during each complete cycle of reciprocating movement thereof, said means comprising a train of gears in constant mesh with said rack and including a cylinder driving gear, a pair of oscillatable gears that are geared to the rack mechanism so that they are oscillated thereby in opposite directions, and a clutch mechanism for alternately driving said cylinder driving gear from each of said oscillatable gears, said clutch mechanism comprising two clutches one of which is associated with each of said oscillatable gears, and clutch-actuating means comprising cam mechanism which ensures that one of the clutches is in engagement before the other is released.

2. A printing press according to claim 1 wherein said cam mechanism includes a rotatable cam and means for rotating said cam in timed relationship to the movement of the bed, said means rotating the cam so as to cause engagement of one clutch and disengagement of the other at the start of one stroke of the bed movement and engagement of both clutches at the end of such stroke.

3. A printing press according to claim 2 wherein the cam is so shaped that for each one-half revolution thereof, one clutch remains in engagement while the other clutch becomes disengaged and remains out of engagement for the major portion of the half-revolution and is again engaged just prior to the completion of the half-revolution.

4. A flat bed and cylinder printing press comprising a reciprocable bed and a rotatable cylinder disposed in cooperative relationship, means for reciprocating said bed with a full harmonic motion, said means comprising a rotatable crank, a reciprocable rack driven by the crank, said reciprocable rack being mounted for reciprocation in a vertical longitudinal plane corresponding to the longitudinal center line of said bed and said crank being in driving engagement with said rack in said plane to prevent the creation of lateral forces thereby, gearing connecting the rack to the bed for reciprocating the bed which is always in driving engagement with the rack and bed, said gearing causing movement of the bed in a direction opposite to the direction of movement of said rack to thereby obtain a counterbalancing effect, means for driving the

cylinder in one direction only at all times through two complete revolutions and so that the peripheral speed thereof coincides with the speed of movement of the bed during each complete cycle of reciprocating movement thereof, gearing connecting said last-named means with said rack and in constant mesh with said rack, said cylinder driving means comprising a cylinder gear which is carried by a rotatably mounted housing for rotation therewith, a pair of oscillatable gears that are geared to the rack mechanism so that they are oscillated thereby in opposite directions, both of said oscillatable gears being disposed on said housing for rotation relative thereto, said housing carrying clutch members for engaging the respective oscillatable gears, and clutch-actuating mechanism comprising a cam disposed within the housing and rotatably mounted thereon for actuating said clutch members, and means for rotating said cam.

5. A printing press according to claim 4 wherein said means for rotating the cam comprises a constantly driven gear disposed in the housing co-axial therewith and mounted for rotation relative thereto, said cam being carried by a shaft disposed radially of the housing and rotatably carried thereby and a pinion carried by said shaft and engaging said driven gear.

6. A printing press according to claim 5 wherein a plurality of said radial shafts and the cams carried thereby are disposed angularly within the housing, each of said clutch members including a ring movable axially of the housing, cam followers carried by the rings, said followers being disposed in pairs with one carried by each ring and engaging the cam at diametrically opposed points.

7. A printing press according to claim 6 wherein each cam is so shaped as to cause engagement of one of the clutch members and disengagement of the other at the start of one stroke of the bed and engagement of both clutches at the end of such stroke.

8. A printing press according to claim 7 wherein the cam is so shaped that for each one-half revolution thereof, one of the clutch members remains in engagement while the other clutch member becomes disengaged and remains out of engagement for the major portion of the half-revolution and is again engaged just prior to the completion of the half-revolution, and wherein each cam is rotated through one-half revolution for each stroke of the bed.

9. A printing press according to claim 5 wherein the gearing connecting the rack to the bed comprises a pinion carried by an oscillatable shaft and engaging the rack, a pair of bed-driving gears carried by such shaft, a pair of racks carried by the bed and engaged by said gears, one of said bed-driving gears being adapted to selectively drive said cylinder driving gear, a second oscillatable gear for selectively driving said cylinder driving gear, said bed-driving gear engaging directly with one of the bed-driving racks, said second oscillatable gear being driven by the same rack through the medium of a pinion drive so that it and the second oscillatable gear will always oscillate in opposite directions, a clutch mechanism for alternately driving said cylinder driving gear from each of the said oscillatable gears, and means for actuating said clutch mechanism.

10. A flat bed and cylinder printing press comprising a reciprocable bed and a rotatable cylinder disposed in cooperative relationship, means for reciprocating said bed, said means comprising crank and rack mechanism, means for driving said cylinder in the same direction at all times, said means comprising a cylinder drive gear that is geared to the cylinder, a pair of oscillatable gears that are geared to the rack mechanism so that they are oscillated thereby in opposite directions, a clutch mechanism for alternately driving said cylinder driving gear from each of said oscillatable gears, a constantly driven gear, and differential means between said last-named gear and said cylinder drive gear for operating said clutch.

11. A printing press according to claim 3 wherein said

oscillatable gears are disposed in axially spaced concentric relationship, a cylinder driving member forming part of said clutch mechanism and disposed concentrically with said oscillatable gears, said cylinder driving member carrying clutch members for engaging the respective oscillatable gears, said rotatable cam being rotatably mounted on said cylinder driving member for actuating said clutch members.

12. A printing press according to claim 11 wherein said means for rotating the cam comprises a constantly driven gear disposed co-axial with said cylinder driving member and mounted for rotation relative thereto, said cam being carried by a shaft disposed radially of said member and rotatably carried thereby and a pinion carried by said shaft and engaging said driven gear.

13. A printing press according to claim 12 wherein each of said clutch members includes a ring movable axially of the cylinder driving member and cam followers carried by the rings in pairs with one carried by each ring and engaging the cam at diametrically opposed points.

14. A flat bed and cylinder printing press comprising a single reciprocable bed and a plurality of rotatable cylinders disposed transversely of the path of movement of the bed and spaced longitudinally thereof for cooperating with type forms to be carried by the bed at properly spaced longitudinal intervals, means for reciprocating the bed with full harmonic motion, said means including crank and rack mechanism, means for rotating all the cylinders at the same speed in one direction only and all in the same direction at all times so that the peripheral speed of each coincides with the speed of the bed and through two complete revolutions for each complete reciprocating cycle of the bed, said means comprising a cylinder driving unit driven by the bed-reciprocating crank and rack mechanism, said cylinder driving unit including a cylinder driving gear driven in the same direction at all times, a pair of oscillatable gears which are oscillated in opposite directions by said crank and rack mechanism, clutch mechanism for driving said cylinder driving gear alternately from said oscillatable gears, means for supporting said cylinders for movement towards and from the bed in synchronism with movement of the bed, transfer mechanism between the cylinders for transferring a sheet from one cylinder to the next, means for driving the transfer mechanism from said cylinders, means for supporting said transfer mechanism for movement with the cylinders towards and from the bed, and means for driving the cylinders from said cylinder driving unit including a set of driving gears arranged between said cylinder driving gear and said cylinders, said driving gears including gears movably mounted to permit vertical movement of the cylinders without interrupting the drive from said cylinder driving gear.

15. A printing press according to claim 1 in which the bed is mounted for reciprocation in a substantially horizontal plane, said reciprocable rack being mounted for reciprocation in a vertical longitudinal plane corresponding to the longitudinal center line of said bed and said crank being in driving engagement with said rack in said plane to prevent the creation of lateral forces thereby, said gearing connecting the rack to the bed causing movement of the bed in a direction opposite to the direction of movement of the rack to thereby obtain a counterbalancing

effect and comprising a pinion carried by a pinion shaft in the plane of the rack and in engagement therewith, bed-driving gears on the pinion shaft and equally spaced on opposite sides of the pinion, and bed-driving racks carried on opposite sides of the bed and engaged by said bed-driving gears.

16. A flat bed and cylinder printing press comprising a reciprocable bed and a rotatable cylinder disposed in cooperative relationship, means for reciprocating said bed with a full harmonic motion and including a pair of oscillatable gears that are oscillated by said reciprocating means in opposite directions, means for driving the cylinder in one direction only at all times through two complete revolutions and so that the peripheral speed thereof coincides with the speed of movement of the bed during each complete cycle of reciprocating movement thereof and including a cylinder driving gear, and a clutch mechanism for alternately driving said cylinder driving gear from each of said oscillatable gears, said clutch mechanism comprising two clutches one of which is associated with each of said oscillatable gears, and clutch-actuating means comprising cam mechanism which insures that one of the clutches is in engagement before the other is released.

17. A flat bed and cylinder printing press comprising a reciprocable bed and a rotatable cylinder disposed in cooperative relationship, means for reciprocating said bed with full harmonic motion, and means operatively connected to the bed-reciprocating means for driving said cylinder in one direction only at all times so that the peripheral surface thereof travels at the same speed as the cooperating linear surface of the bed and the cylinder rotates through two complete revolutions for each reciprocating cycle of the bed.

18. A flat bed and cylinder printing press according to claim 17 wherein the means for reciprocating the bed comprises a rotatable crank, a reciprocable member connected to and reciprocable by the crank, and a connection between the reciprocable member and the bed for always moving the bed in a direction opposite to the direction of movement of the reciprocable member thereby to obtain a counterbalancing effect.
